US00D616782S

(12) **United States Design Patent**
Chastaingt

(10) **Patent No.:** **US D616,782 S**
(45) **Date of Patent:** **** Jun. 1, 2010**

(54) **WATCH DIAL**

(75) Inventor: **Arnaud Chastaingt**, Paris (FR)

(73) Assignee: **Cartier Creation Studio SA (CH)**

(**) Term: **14 Years**

(21) Appl. No.: **29/356,997**

(22) Filed: **Mar. 5, 2010**

(51) LOC (9) Cl. **10-07**

(52) U.S. Cl. **D10/126**

(58) **Field of Classification Search** D10/122-126,
D10/30-39; 368/80, 223, 228, 232

See application file for complete search history.
